UNITED STATES PATENT OFFICE.

JOSEPH W. FISKE, OF NEW YORK, N. Y.

DESIGN FOR ORNAMENTAL VASE.

Specification forming part of Design No. 7,430, dated May 12, 1874; application filed April 21, 1874.
[Term of Patent 7 years]

O.

To all whom it may concern:

Be it known that I, J. W. FISKE, of New York, in the county of New York and State of New York, have invented certain Improvements in Designs for a Pedestal for Vases, Statuary, &c., of which the following is a specification:

The nature of my design is fully represented in the accompanying photographic illustration.

This is a design for a stand or pedestal for supporting an urn or vase, or for any similar purpose, usually made of metal. As shown in the accompanying illustration, it has a rectangular base, supporting a corresponding body and cap-piece. The base is joined to the body by a series of ornamental moldings, *a*, *b*, *c*, *d*, and *e*, the lower one, *a*, being covered on its surface with a series of leaves or similar figures, while the remaining members of the

moldings are plain. Upon each face or side of the body is a sunken panel, *f*, the top of which is curved downward, and each of the angles or corners *g* of the body is cut away or beveled the greater portion of their length. Upon each face, above the panel *f*, is a raised or projecting portion, *h*, on which is formed a scroll, as shown. The cap or top portion projects laterally beyond the sides of the body, with a molding around its lower edge, and with its upper edge of an ogee form, as shown.

What I claim as my invention is—

The herein-described design for a stand or pedestal for supporting vases, statuary, or similar purposes.

JOSEPH W. FISKE.
